CLAIM

The ornamental design for a lash assembly, as shown and described.

DESCRIPTION

FIG. 1 is a perspective view of a lash assembly showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top perspective view of the lash box component of the lash assembly;

FIG. 9 is a top perspective view of the lash tray component of the lash assembly;

FIG. 10 is a bottom perspective view thereof;

FIG. 11 is a perspective view of the lash assembly with fake eyelashes; and,

FIG. 12 is a perspective view of the lash assembly housed with additional lash assembly kits in a stacked configuration. The broken lines of the lash assembly depict portions of the lash assembly that form no part of the claimed design. The broken line outlines of the fake eyelashes in FIGS. 11-12, the additional lash assemblies in FIG. 12, and an outer box of the lash assemblies in FIG. 12 depict environmental structure associated with the claimed design but form no part of the claimed design.
